UNITED STATES PATENT OFFICE.

CHRISTIAN F. BREMER, OF TAMPA, FLORIDA.

CIGAR-ASSORTING DEVICE.

Application filed December 8, 1921. Serial No. 521,065.

To all whom it may concern:

Be it known that I, CHRISTIAN F. BREMER, a citizen of the United States, residing at Tampa, in the county of Hillsboro and State 5 of Florida, have invented certain new and useful Improvements in Cigar-Assorting Devices; and I do hereby declare the following to be a full, clear, and exact description of the invention, such as will enable others 10 skilled in the art to which it appertains to make and use the same.

This invention relates to methods and apparatuses for sorting cigars, and particularly to methods and apparatuses for sorting cigars 15 according to their colors, and shades.

Ordinarily it is difficult and tedious to sort cigars according to their colors and shades because of the fact that there are so many different shades in a lot of cigars, and 20 the use of samples is rendered necessary. These samples must be placed at a point which will make it easy for the person sorting the cigars to bring the cigar in close proximity to the sample, for the purpose of getting 25 all of a single shade or nearest thereto, in a group for passage to another person for packing. The samples have been so located that the sorter could not properly match the cigars with the samples, thus causing a collection 30 of a number of cigars of various shades in a sample group. It is the particular object of the present invention to provide a device wherein the sorter must pass the cigar directly over the sample in placing 35 the cigar in its proper group, with the result that the cigars are more perfectly matched.

Another object is to provide a tray in which the cigars are stacked according to 40 their shades, which tray is arranged to properly and conveniently support the cigar samples, and wherein the different stacks of cigars will be held in their appropriate groups.

Another object is to provide a sample holder which is so constructed and applied to the tray that the rows of cigars in each stack will be held in proper position, and wherein, as the stack grows in height, the 45 holders may be elevated to properly hold the stacks.

Other objects and advantages will be apparent from the following description when taken in connection with the accompanying 50 drawing.

In the drawing:

Figure 1 is a top plan view of a tray for sorting cigars, made in accordance with the present invention.

Figure 2 is a front elevation of a portion 60 of the tray, showing the sample holders.

Figure 3 is a vertical sectional view through a portion of the bottom of the tray and one of the sample holders, on the line 65 3-3 of Figure 2.

Figure 4 is a perspective view of one of the sample holders removed from the tray.

Referring particularly to the accompanying drawing, 10 represents the bottom of the tray in which the cigar stacks are arranged by the sorter, said bottom having a central recess 11 in its front edge face within which the sorter stands while selecting and sorting the cigars. Formed in the bottom 10 and extending in a direction transversely of the sorter, are parallel series of elongated slots 12. In each of the slots 12 is removably disposed one of the cigar sample holders which will now be described.

The sample holder includes a vertical 70 stem 13 formed from a sheet of suitably stiff metal, and a transverse head 14 secured on the upper end of the stem. The head 14 is formed from a strip of wood having a longitudinal kerf or groove 15 in its lower face 75 within which the upper end of the stem is secured. In the upper face of the wood strip 14 there is formed a longitudinal transversely curved groove 15' having a high side and a low side, and secured to one vertical face of the head and rising above the low side of the groove, is a strip of soft rubber 80 16, said upper portion of the rubber serving as the other wall of the groove thus formed in the upper face of the head. Between the 85 rear wooden wall, and the front soft rubber wall, the cigar sample 17 is held, the rubber performing the function of a clamping jaw 90 to hold the cigar.

It will be noted, upon reference to Figures 1 and 2, that there is a sample holder in each of the slots of the bottom of the tray, and that the holders are spaced a sufficient distance apart to accommodate the ends of the cigar samples, without interference thereof. 100 The cigars are placed behind the holders, so that the first cigar placed on the bottom of the tray will rest against the head of the holder, the next cigar is placed behind the first cigar, and so on until the row reaches 105 110

the next line of holders, when a second row is formed on top of the first row. Before placing the second row in position, the holder is pulled upwardly to such a distance 5 that the lower face will partially rest on the first cigar of the row. The rest of the row is then placed in position. Each time that a row is completed the sample holder is lifted up sufficiently to permit the head 14 to rest 10 on the first cigar of the next row.

This construction and arrangement permits the sorter to bring each cigar close to the sample, before placing the cigar in the proper stack, on the bottom of the tray, 15 with the result that more perfect matching can be accomplished. Of course, it is impossible to select a number of cigars of exactly the same shade as the sample, because of the fact that out of a thousand cigars 20 there will be approximately four or five hundred different colors and shades. Sometimes there will be several shades from the same leaf.

What is claimed is:

- 25 1. A cigar sorting device comprising a tray having slots in its bottom arranged in parallel series, removable members disposed in the slots and being arranged in regularly spaced relation, and a cigar sample holding 30 means on each of the removable members.
2. A cigar sorting device comprising a tray having its bottom formed with parallel series of elongated slots, stems removably disposed in the slots to form longitudinal 35 series of cigar stack retaining walls, and a cigar sample holding means on the upper

end of each of the stems and including a rigid clamping jaw and a flexible clamping jaw.

3. A cigar sorting device including a tray 40 and cigar sample supporting means carried thereby, each of said sample supporting means consisting of a stem, a transverse head on the upper end of the stem, the head having a stationary rigid jaw, and a flexible 45 jaw on one face of the head and cooperating with the rigid jaw to hold a cigar sample therebetween.

4. A cigar sample supporting device comprising a flat stem, a transverse head on the 50 stem having a longitudinal groove one side wall of which forms a vertical rigid jaw, and a flexible rubber strip secured to the head and projecting above the adjacent side thereof to cooperate with the rigid jaw. 55

5. In a cigar sorting device a tray having its bottom formed with a plurality of series of elongated slots and cigar sample holders comprising vertical flat stems and cigar sample clamping jaws on the upper end thereof, 60 the jaws being arranged to rest on the uppermost cigar of a stack placed behind a stem, the stem being arranged to perform the function of a retaining wall for the cigar stack. 65

In testimony whereof, I affix my signature in the presence of two witnesses.

CHRISTIAN F. BREMER.
